INVENTOR
Daniel Kirk
BY
W. F. Beeler
ATTORNEY

UNITED STATES PATENT OFFICE.

DANIEL KIRK, OF GLEN COVE, NEW YORK.

RADIOHORN.

Application filed February 2, 1927. Serial No. 165,270.

This invention relates to sound producing or modifying means and has particular reference to sound amplifying means intended for use in connection with loud speakers of 5 radio equipment or the equivalent.

Among the objects of the invention is to provide a horn structure designed particularly for augmenting the sound delivered from or through a loud speaker and with 10 such quality as to render the same delightfully soft in quality and natural in character.

With the foregoing and other objects in view the invention consists in the arrangement and combination of parts hereinafter described and claimed and while the invention is not restricted to the exact details of construction disclosed or suggested herein, still for the purpose of illustrating a 15 practical embodiment thereof reference is had to the accompanying drawings in which like reference characters designate the same parts in the several views, and in which—

Figure 1 is a vertical central transverse 25 section of my improvement.

Fig. 2 is a front elevation of the same.

Fig. 3 is a horizontal section substantially on the line 3—3 of Fig. 1 and with parts broken away.

Fig. 4 is a horizontal section on the line 30 4—4 of Fig. 1.

Fig. 5 is a vertical sectional detail on the line 5—5 of Fig. 3.

Referring now more specifically to the 35 drawings I show a horn construction comprising three main parts—a tapered body portion or horn proper 10, a base 11, and a head portion 12.

The body 10 comprises a series of nested 40 members having approximately similar form in cross section and indicated herein as of square section, but to which form I do not propose to be unnecessarily limited in practice. The several parts of the body as 45 shown herein and as practised by me extensively, comprise an outer tubular shell or casing 13, the same being tapered or of frusto-pyramidal form, tapering and flaring upward from the small end 13^a, shown 50 herein as being at the bottom. This shell or casing 13 is made preferably of wood of uniform thickness. Within the shell 13 is a composite resonator 14, coextensive in length with the shell 13, and consisting of 55 two tubular portions 14^a and 14^b, the former being within the latter and the two being

secured intimately and rigidly together as by means of cement indicated at 14^c. The inner part of the resonator is formed preferably of a good quality of heavy cardboard, 60 while the outer portion thereof 14^b consists of sheet metal such as a good quality of galvanized iron. The lower end of the resonator is fitted or built snugly in the lower end 13^a of the shell 13, and secured to the ends of these parts is a cap 15 of any suitable material such as wood which is adapted to be secured to the lower end of the shell 13 as by means of cement, screws, 65 or other fasteners, the cap having a central hole 16 into which the nipple 17 of the loud speaker 18 is adapted to be secured as by screwing, the nipple end of the loud speaker thus communicating with the small mouth portion 14^d of the resonator. 75

Any suitable means may be provided to support the horn body and in order to hold it erect as indicated, I provide a base comprising a plurality of legs 11^a having spaced feet to rest upon the floor and provide a 80 clear space for the application and accommodation of the loud speaker and whatever connections may be required for it. These legs are shown glued or otherwise secured to the respective outer surfaces or walls of 85 the shell 13.

The resonator 14 toward its upper or bell end has less flare than has the shell 13 and consequently there is left a tapering space 19 between the shell and the resonator, said 90 space having its widest area at the bell end of the horn body, it flaring all the way from zero at the loud speaker end up to the bell end, and since the parts or elements making up the parts are straight, this taper or flare 95 is uniform throughout the length of the body. Except for the flare just described, the body 10 is constructed of straight elements, having no pronounced bell formation in itself. The resonator while having snug 100 contact in and with the shell at the end 13^a, is free therefrom all the way between the ends. The bell end of the resonator must be supported so as to maintain the proper spacing of substantial uniform dimension 105 with respect to the shell 13, and as a result of extensive careful experiments, I have discovered that the spacing means are of peculiar construction or character to produce the best results. For example, blocks of 110 wood, pins, or the like interposed between the resonator and the shell proved unsatis-

factory. Consequently what I employ for this purpose and which I believe to be the best adapted as tie or spacing means are a plurality of tie members in the form of 5 pieces of tape 20, each of which has one end glued or otherwise secured upon the inner surface of the resonator and extended thence upward and outward across the edge of the resonator and thence directly and horizontally 10 across the proximate edge of the bell portion of the casing 13 where it is secured as by means of fasteners 21 or their equivalent driven into the end of the shell wall. In practice the end on the 15 inside of the resonator is secured in place first, and then while the tape is still a part of a long piece, it is drawn outward as described by force applied to the bulk portion of the tape, whereby a substantial degree of 20 tautness is produced in the tie member.

The head 12, secured to the bell end of the body 10, is of materially larger expanse and constitutes in effect a sound delivery bell. This structure as viewed in front and side 25 elevations is illustrated as substantially rectangular, but as viewed in plan or horizontal section, it is preferably made wider in front than at the rear.

The structure as shown comprises a casing 30 having a grille-like or reticulated front wall 22, a narrow rear wall 23, and vertical side walls 24, flaring from each other as they approach the end edges of the grille 22. The casing is also provided with a bottom panel 35 25. The meeting edges of all these parts are glued or otherwise united firmly together and they are all imperforate except for the open grille of the front panel 22 and a sound delivery opening 26 in the bottom 40 panel 25 registering and communicating with the air space 19 of the body and the resonator. The sound opening 26 is spaced from the edges of the panel 25 but is located preferably back of the center thereof or closer 45 to the rear wall 23 than the front wall of the head.

Within the shell just described is a sound dome or reflector 27 which is made preferably as a segment of a hollow cylinder, the axis of which is located at some convenient point below and in front of the head. This dome is secured at its lower edge adjacent to the joint between the bottom panel 25 and the lower edge of the rear panel 23 of the shell and it curves thence upward and forward till its front upper edge communicates with the shell at the joint between the front panel 22 and the top panel 28, whereby the sound delivered through the opening 26 is deflected upward and forward without material distortion and with a pronounced augmentation of the volume and softness and purity of timbre. The head is secured rigidly and tightly to the upper edge of the bell and the shell 13, any 60 suitable fasteners with or without glue being used for this purpose. I show, however, the application of glue at 29. The dome 27 is made preferably from the same kind of material as is used for the inner portion of the 65 resonator, a material not only well adapted for the formation of the curved structure, but one which is peculiarly suitably adapted for the tonal or musical effect. 70

I claim:

1. The herein described sound amplifier comprising an outer wooden horn, an inner horn spaced therefrom, the inner horn being a fibre horn having a metal sheathing, the said horns enlarging toward their ends, and 80 flexible adhesive tape securing the horns in predetermined spaced relation at said ends.

2. The herein described sound amplifier comprising an outer wooden horn, an inner horn spaced therefrom, the inner horn being made of a rigid material interiorly lined with a papery material, and flexible tape securing the horns in predetermined spaced 85 relation.

In testimony whereof I affix my signature.

DANIEL KIRK.
